UNITED STATES PATENT OFFICE.

MARTHA L. HUNTER AND ALBERT B. CHURCH, OF SAN FRANCISCO, CALIFORNIA.

ANNOTATOR FOR COMMERCIAL PHONOGRAHS.

1,230,485.

Specification of Letters Patent. Patented June 19, 1917.

Original application filed September 15, 1915, Serial No. 50,780. Divided and this application filed January 25, 1917. Serial No. 144,564.

To all whom it may concern:

Be it known that we, MARTHA L. HUNTER and ALBERT B. CHURCH, both citizens of the United States, residing at the city and county of San Francisco and State of California, have invented new and useful Improvements in Annotators for Commercial Phonographs, of which the following is a specification.

10 This invention relates to commercial phonographs, and is a division of our pending application, Serial No. 50,780, filed September 15, 1915.

15 The object of this invention is to provide an attachment for a transcribing phonograph whereby from a memo sheet previously marked up with various instructions applying to the matters contained in the phonograph record, the transcriber may locate upon the record the position of the matters to which said instructions apply.

20 Heretofore, it has been proposed to supply a specially printed sheet, properly ruled and provided with stock phrases, said sheet to receive upon its face penciled marks made by the dictator to convey the necessary information relative to the matters in the record for the convenience of the transcriber. Great difficulty has been encountered by 25 users of this memo sheet in properly locating from the marks thereon the position in the phonograph record of the matters to which such marks apply.

30 In the present invention this objection has been overcome by the provision of mechanical means for carrying on these operations, whereby greater precision and accuracy are obtained.

35 In carrying out the object of this invention we employ a holder, fastened to the box of the transcribing phonograph, to receive sheets of memo paper previously marked with various instructions relating to the matters contained in the phonograph record, and 40 means movable with the traveling head of the phonograph to indicate in advance to the transcriber the exact position and location on the phonograph record of the matters to which the marks on the sheet apply.

45 One form which our invention may assume is exemplified in the following description and illustrated in the accompanying drawings, in which—

Figure 1 shows a front elevation of the

transcribing attachment applied to a phonograph.

Fig. 2 shows a side elevation of the device illustrated in Fig. 1.

In the drawings, a phonograph is shown comprising a box 10, a cylindrical record 11, and a movable head 12. The latter is provided with a reproducer 13. Attached to the front side of the box, by suitable brackets 14 and thumb-screws 15, is a holder 16.

A sheet 17 is marked during the process of dictating with various instructions applying to the matters contained within the record. It should indicate whether a letter should be single or double spaced; the location of letters and telegrams which should be transcribed first; letters of which extra copies are required, etc.

When transferring the record to the transcribing machine, the memo sheet is introduced in the holder 16. This holder 75 comprises a base plate carried in inclined position with flanged sides 18, on the ends of which are spring-pressed clips 19 pivoted to rods 20, for retaining the sheet in a flattened position thereon. Rigidly connected 80 to the reproducing device 13 of the transcribing machine is an indicator plate 21 positioned to travel across the holder and provided with indicating notches 22 labeled to correspond with the items on the memo 85 sheet. Thus the operator is enabled to locate the position of the various matters in the record to which the marks on the memo sheet apply merely by sliding the reproducing device, to which the indicator plate is attached upon the record, until the notches on said plate register with the various marks on the paper. These marks, while here shown in the form of dots, may be of any nature, or may be the printed word itself. 95

Various changes in construction and arrangement of the parts may be employed without departing from the spirit of our invention as disclosed in the appended claims.

Having thus described our invention, what we claim and desire to secure by Letters Patent is—

1. In combination with a commercial phonograph and a holder rigidly connected thereto, a stationary sheet having longitudinally arranged instructions thereon carried by said holder, and an indicator connected to the traveling head of the phonograph and

extending over and across said sheet, said indicator having indicia thereon extending transversely thereof and in alinement with the respective longitudinally arranged instructions of said sheet.

2. In combination with a commercial phonograph, an inclined holder, brackets connected to the holder and formed with right angled parts to engage over the front and top meeting edges of the phonograph case, a stationary sheet having longitudinally arranged instructions thereon carried by said holder, and an indicator connected to the traveling head of the phonograph and

extending over and across said sheet, said indicator having indicia thereon extending transversely thereof and in alinement with the respective longitudinally arranged instructions of said sheet.

In testimony whereof we have hereunto set our hands in the presence of two subscribing witnesses.

MARTHA L. HUNTER.
ALBERT B. CHURCH.
